UNITED STATES PATENT OFFICE.

HENRY F. HAVENS, SR., OF HUDSON FALLS, NEW YORK.

FOLDING TABLE.

1,339,389.

Specification of Letters Patent. Patented May 11, 1920.

Application filed May 22, 1919. Serial No. 299,053.

To all whom it may concern:

Be it known that I, HENRY F. HAVENS, Sr., a citizen of the United States, residing at Hudson Falls, in the county of Washington and State of New York, have invented certain new and useful Improvements in Folding Tables; and I do declare the following to be a full, clear, and exact description of the invention, such as will enable others skilled in the art to which it appertains to make and use the same.

This invention relates to folding tables.

One object of the invention is to provide an improved spring means for swinging two opposite legs of the table to the position for supporting the table leaves when permitted to do so by the raising of the leaves to horizontal position.

Another object of the invention is to provide an improved two-piece strut or leg-brace which effects a reduction in the cost of manufacture and permits the table to be disassembled, when repairs are necessary without detrimentally affecting any part of the table.

Other objects and advantages may become apparent to persons who read the following details of description in connection with the accompanying drawings, in which:

30. Figure 1 is an end elevation of the table in its useful or extended position.

Fig. 2 is an end elevation of the table in its collapsed or folded position.

Fig. 3 is a bottom plan view.

35. Fig. 4 is a central vertical sectional view showing the leaves extended and supported by the pivotally mounted leaf-supporting frame.

Fig. 5 is a horizontal sectional view substantially along the line 5—5 of Fig. 2.

Fig. 6 is a horizontal sectional view along the line 6—6 of Fig. 1.

Fig. 7 is a perspective view illustrating the component members of one of the leg-braces or struts, these component parts being slightly separated so as to fully disclose their respective outlines and their relation to one another.

Referring to these drawings in detail, in which similar reference characters correspond with similar parts throughout the several views, and in which the table top may be of ordinary construction, comprising a central stationary portion 8 to which leaves 9 are hinged at 10:

My invention consists in the special and

novel form of pivotal connection and spring unfolding means which will now be described in detail.

The table top portion 8 is united with a stationary frame 11 which comprises legs 12, an upper strut 13 and a lower strut 14, the latter being preferably of the two-piece construction illustrated separately in Fig. 7, it being understood that the strut 13 may also be of the two-piece construction instead of the one-piece construction disclosed in the drawings. The leaf-supporting frame 15 also comprises legs 12, the upper strut 16 of this frame being complementary to the upper strut 13 of the frame 11, and the lower strut 17 of this frame being complementary to the lower strut 14 of the stationary frame 11. That is, the intermediate portions of the struts are cut away above and below, respectively, while their end portions are reduced in thickness, so that when pivotally connected at their centers, they may be folded in such relation that the legs 12 may be brought into juxtaposition, in pairs, as illustrated in Fig. 2. This manner of folding a table is not claimed as being new, and will be understood by persons familiar with the art, without further explanation. However, a novel and improved feature of this invention resides in the pivotal connection most clearly illustrated in Figs. 4 and 6, in which an upper tubular pivot 18 and a lower tubular pivot 19 constitute means for pivotally connecting the leaf-supporting frame 15 to the stationary frame 11. The purpose of providing tubular pivot elements is to permit a torsional spring 20 to be disposed concentrically with the pivotal connection of the frames 11 and 15. A slotted plate 21 is secured to the lower strut 14, and the lower end of the flat torsional spring or bar 20 is non-rotatably seated in the slot of the plate 21, or in other words, the lower end of the spring 20 is normally fixed with relation to the leaf-supporting frame. A slotted plate or disk 22 is normally fixed to the stationary frame 15, and the upper end of the spring 20 is non-rotatably seated in the slot of the disk 22. However, arcuate slots 23 may be provided in the disk 22, and screws 24 extend through these slots into the upper strut 13 and secure the disk 22 in any position to which it may be adjusted, it being understood that adjustment may be made by loosening the screws 24, turning the disk 22 until the spring 20 is tensioned, as desired, and then

tightening the screws 24. In order that access may be had to the disk 22 and its adjuncts, an aperture 25 may be provided in the center of the top portion 8, and a plate 26 5 may be countersunk in the member 8 so as to be flush with the top surface of the table while closing the aperture 25. When it is desired to change the tension of the spring 20, the plate 26 may be removed, and any appropriate tool or other means may be employed 10 to engage with the upper end of the spring 20 or with the plate 22 for turning the latter. For the purpose of guarding the spring 20, and for holding the frames 11 and 15 in proper relation to one another when the 15 table top is detached, a tube 27 may have its upper end embedded in and abutting against the upper strut 13 of the stationary frame, while its lower end is embedded in and abuts 20 against the lower strut 17 of the pivotally mounted frame. It will be seen that the tube 27 co-operates with the pivot elements 8 and 9 for holding the top-supporting frames in pivotal connection with one another when the table top is removed, it being understood that screws or other securing means (not shown) may be employed 25 for removably securing the top to the stationary frame.

30 From the foregoing, it will be seen that the spring 20 may be adjusted to either fold or unfold the top supporting frames, and it will probably be usually preferable to adjust the spring so that it will unfold the supporting frames when allowed to do so by extending the leaves 9 from the folded position shown in Fig. 2 to the unfolded position shown in Fig. 1. Stops or abutments 28 may be provided on the leaves 9 35 to limit the opening or unfolding movement of the pivoted frame 17 so that it stands substantially at right angles to the stationary frame.

In order that the frames may be constructed 40 separately and afterward inter-linked with one another, as illustrated in the drawings, and in order that time, labor and material may be saved in the manufacture of the two-piece struts shown in Fig. 7, 45 each half or separate section of such strut is formed separately and afterward separably secured together by means of screws or bolts, as indicated at 29. It will be seen that each section 14' (for instance) of the strut 14, is of counterpart construction, and therefore, separate patterns and forming means are unnecessary for the elements 14'. Moreover, each section of the strut 17 is of 50 counterpart construction, and the only difference between the struts 14 and 17 is the difference in size and shape of their central apertures which receive the tubular elements 19 and 27. It will be seen, therefore, 55 that substantially the same pattern and forming devices may be used for both of

the lower struts, thereby saving much expense and confusion in providing and carrying for numerous patterns and tools. Moreover, in the event that a lug or other portion of the table should become broken or need 70 repairing, the table is easily disassembled so as to effect the needed repairs with the least trouble and inconvenience, and without detrimentally affecting any portion of the table.

Although I have described this embodiment of my invention very specifically, it is not intended to limit this invention to these exact details of construction and arrangement, but changes may be made within the scope of the inventive idea as described and 75 claimed herein.

What I claim as my invention is:

1. The combination in a table, of a top portion, a leaf hinged thereto, a top-supporting frame under said top portion, a leaf- 85 supporting frame movably secured to the said top-supporting frame by an axially- vertical pivotal connection, and a torsional spring alined with the axis of said pivot and having its ends secured respectively to 90 said top-supporting frame and said leaf-supporting frame.

2. The combination with a table comprising hinged leaves and a pivotally mounted leaf-supporting frame, of a torsional spring, 95 means at the pivotal connection of said frame to non-turnably secure one end of said spring to said frame, and means at said pivotal connection for securing the other end of said spring in normally non-turnable 100 relation to said leaves but in such adjustable relation that the tension of said spring may be changed at will of the user.

3. The combination in a table comprising hinged leaves and a leaf-supporting frame, 105 of tubular pivot elements on which said frame is swingable into and out of the leaf-supporting position, and a torsional spring extending through said tubular pivot elements and having one end normally fixed 110 with relation to said leaves, the other end of said spring being normally fixed with relation to said leaf-supporting frame.

4. The combination in a table comprising 115 a central top portion, leaves hinged thereto, a stationary supporting frame, and a pivoted leaf-supporting frame, each of said frames comprising upper and lower struts, of a vertical tube having its upper end embedded in the upper strut of said stationary 120 frame while its lower end is embedded in the lower strut of the pivoted frame, and a torsional spring extending through said tube and having its upper end normally fixed to said stationary frame, its lower end 125 being normally fixed to said pivoted frame.

5. In a table-leaf supporting frame, the combination of a pair of legs, and a pair of spaced struts, one of said struts comprising a pair of strut-forming members of sub- 130

stantially counterpart construction, each of said strut forming members having its outer end united with one of said legs, the inner end portions of said strut-forming members being interlapped with one another and rigidly but separably secured together, so that this frame can be assembled with a similar

frame, in the relation shown, after the legs are permanently united with the struts, substantially as described.

In testimony whereof I have hereunto set my hand.

HENRY F. HAVENS, Sr.
